Fig. 3

Fig. 1

Fig. 2

FIG. 1 is a front elevational view of a motorcycle dash panel showing my new design;

FIG. 2 is a front elevational view of a motorcycle dash panel showing a second embodiment of my new design; and

FIG. 3 is a typical side elevational view of the motorcycle dash panel shown in FIGS. 1 and 2, it being understood that the opposite side is a mirror image thereof.

The top and bottom of the motorcycle dash panel are substantially plain, while the rear thereof is flat and unornamented.

I claim:

The ornamental design for a motorcycle dash panel, as shown and described.
